UNITED STATES PATENT OFFICE.

GRANVILLE E. PALMER, OF BOSTON, MASSACHUSETTS, ASSIGNOR OF ONE-FOURTH TO CHARLES B. PRICE AND ONE-FOURTH TO F. S. PRICE, OF BOSTON, MASSACHUSETTS.

ELECTRICAL CONNECTOR.

No. 923,071.

Specification of Letters Patent.

Patented May 25, 1909.

Application filed November 21, 1906. Serial No. 344,427.

To all whom it may concern:

Be it known that I, GRANVILLE E. PALMER, a citizen of the United States of America, residing in the city of Boston, in the county of 5 Suffolk, in the State of Massachusetts, have invented a certain new and useful Improved Electrical Connector, of which the following is a specification.

The object of my invention is to provide a 10 simple and inexpensive, but efficient, electrical connecting device, particularly adapted for use in making ground connections on pipes and cables, and especially for making electrical connections to lead cables to 15 ground them.

In the accompanying drawings Figure 1 is a perspective view of my connector detached; Fig. 2 is a side view of the connector attached to a pipe or cable; Fig. 3 is a cross- 20 section on the line 3—3, Fig. 2; Fig. 4 is a perspective view; and Fig. 5 is a cross-section of a modification.

I take a strip of copper or other suitable conducting material and of a convenient 25 width, and bend it up into about the shape shown in Figs. 1 and 4, that is to say, into the form of a clip with a hooped part 5 adapted to be fitted to and to embrace the pipe or cable 4, and with two wings or free ends, 6 30 and 7, with which I combine connecting means to clamp the looped part of the connector on the pipe or cable. In the present instance these connecting means are shown as consisting of headed bolts 8 passing 35 through holes 9 in the wings 6, 7, and provided with screw nuts 10. Instead of having closed holes for the bolts in both wings, as shown in Figs. 1 and 2, I prefer to make the holes in the wing 7 in the form of notches 40 19, as shown in Figs. 4 and 5, and to upset the ends of the bolts at 18 to prevent the nuts from being lost, as will be readily understood.

One of the wings, 6, has its outer edge 45 curled or rolled over inward to form a tube 11, lying in the direction of the length of the pipe or cable. This tube 11 is of a diameter to form a socket to receive with a snug fit the bared end of the electrical conductor 12,

which is to be soldered to the clip. By this 50 provision of a socket lying in the direction of the length of the pipe or cable, the conductor 12 can be more conveniently connected up than where the socket is at right angles, as is the common way. And the fact that the 55 socket is open at opposite ends makes it further convenient to attach the conductor at either end, and at the same time the wireman is enabled to readily see that he gets his wire in the full length of the socket to make 60 a thoroughly good electrical and mechanical joint.

The wing 7 is of a length to enable its outer end to bear against the outer face of the tube 11 at the middle of the tube, when the two 65 wings are drawn up toward each other. This will tend to prevent the corners 13 of the clip from being forced into a soft lead cable, as might occur, to the injury of the cable, if the wing 7 were short enough to pass 70 under the tube 11 and the bolts and nuts 8 and 10 were to draw the wings too close together.

I claim as my invention—

1. An electrical connector, comprising a 75 clip to embrace a pipe or cable and having free ends, one of which has a wire receiving socket, while the other free end is adapted to bear against the middle of said socket, and bolt and nut means passing through the free 80 ends to draw them toward each other.

2. An electrical connector, comprising a strip of sheet metal bent into the form of a clip to embrace a pipe or cable and having free ends, with bolt and nut means to draw 85 the free ends toward each other, one of said free ends having, beyond the bolt and nut means, a projecting face against the outer edge of which said other free end may bear as the bolt and nut means are tightened, as and 90 for the purpose described.

In testimony whereof I have signed my name to this specification, in the presence of two subscribing witnesses.

GRANVILLE E. PALMER.

Witnesses:

ROGER H. WILDE,
I. W. CROWELL.
